(57) **CLAIM**

The ornamental design for an automotive docking station, as shown and described.

DESCRIPTION

FIG. 1 is a rear perspective view of an automotive docking station according to a first embodiment thereof;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof;

FIG. 8 is a rear perspective view of an automotive docking station according to a second embodiment thereof;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top view thereof;

FIG. 14 is a bottom view thereof; and,

FIG. 15 is a rear perspective view thereof shown in connection with additional environmental features that can be associated therewith.

The features shown in broken lines are environmental only and form no part of the claimed design.

Dash-dot lines adjacent un-shaded areas represent bounds of the claimed design and themselves form no part of the claimed design.
